UNITED STATES PATENT OFFICE.

CHARLES WILLIAM SANDERS, OF VICTORIA, BRITISH COLUMBIA, CANADA.

SHEET-METAL PARTITION.

1,111,617.

Specification of Letters Patent. Patented Sept. 22, 1914.

Application filed July 24, 1913. Serial No. 780,971.

To all whom it may concern:

Be it known that I, CHARLES W. SANDERS, a subject of the King of Great Britain, and a resident of Victoria, in the Province of British Columbia, Dominion of Canada, have invented a new and Improved Sheet-Metal Partition, of which the following is a full, clear, and exact description.

It is a design of my invention to provide a partition to receive metal lathing and formed of sheet metal instead of more solid cast or rolled metal elements, whereby the partition may be much more cheaply produced.

15 It is a further design of my invention to provide a metallic partition in which the elements may be quickly and conveniently assembled, and produce a strong and durable structure on which the lathing may be readily applied.

The invention also has for its design to produce a partition in which the studding elements are braced by self-fastening stiffeners.

25 The invention furthermore has for its design to provide a metallic partition having at the top and bottom thereof channel plates that may be relied upon to prevent fire from creeping through the ceiling or along the 30 floor, should the plaster crack at either place.

The novel features of the invention will be more particularly explained in the specific description following.

35 Reference is to be had to the accompanying drawings forming a part of this specification, in which similar characters of reference indicate corresponding parts in all the views.

40 Figure 1 is a partly sectional face view of a portion of a partition embodying my invention; Fig. 2 is a partly sectional plan view; Fig. 3 is a transverse vertical section; Fig. 4 is a perspective view of a portion of 45 one of the plates forming the top and bottom of the partition; Fig. 5 is a perspective view of a portion of one of the studding elements; and Fig. 6 is a perspective view of a portion of one of the stiffeners formed with 50 integral members for fastening the stiffeners to the studding.

In forming a partition in accordance with my invention a top plate 10 is provided, and a bottom plate 11 having a channel form in 55 cross section. Studding elements 12 suitably spaced apart are received at their up-

per and lower ends between the side flanges 13 of the top and bottom plates, and between adjacent studding elements stiffeners 14 extend. Each stiffener is formed with integral fastening members 15, 15^a, and these are produced in sets of three, and preferably are V-shaped, the plate being first formed with cuts 16 in V-form, as shown in Fig. 6, there being one V-shaped cut oppositely disposed and adjacent to a pair of such cuts, the arrangement being such that three tongues may be struck up from the plate at an angle normal to a face of the stiffener, to produce the V-shaped fastener members 15, 15^a, the pair of fasteners being spaced from the single fastener a distance equal to the thickness of the web or body of a studding element 12, and the single fastener being in staggered relation to the adjacent pair. The stiffener is secured by passing the same through transverse slots 12^a in the studding elements and then bending up the pair of tongues 15 at one side of the studding, and the single tongue 15^a at the opposite side of the studding, so that the studding will be gripped between a pair of fastening tongues and an adjacent single tongue.

55 The studding elements 12 are preferably formed in Z-shape, to present vertical flanges 12^b projecting oppositely along the vertical edges, the flanges serving to give a proper bearing between the studding elements and the flanges 13 of the top and bottom channel plates. The illustrated form of the studding also produces increased strength, while at the same time permitting of the compact assemblage of the studding elements for shipping and storing.

60 The web or body of each studding element is formed with elongated, vertically ranging slots 12^c adjacent to each flange 12^b, for receiving ties 17 for tying the metallic lathing 18 to the studding. The end slots 12^c accommodate tie wires 19 for tying the top and bottom plates to the studding, said ties 19 being passed through said end slots 12^c and through holes 10^a in the flanges 13 of the top and bottom channel plates. 65 As seen best in Fig. 4, the channel plates are formed also with slots 10^b to receive ties 20 for fastening the upper and lower edges of the lathing 18 to the said plates.

65 It will be seen that the tongues 15 arranged as shown, provide the stiffeners 14 with self-fastening means by which the

stiffeners are secured to the studding, without the employment of adventitious devices in the way of rivets, etc.; also, as seen in Fig. 3, the metallic lathing 18 is in the vertical plane of the flange 13 of the top and bottom channel plates, at each side of the latter, and said channel plates form closed upper and lower ends for the partition. Thus, should the plaster on either face of 10 the partition crack during a fire, the flame will be cut off from passing upwardly through the partition along the ceiling, or downwardly and along the floor. As a result also of the improved structure, the lathing 15 is very solidly supported and securely fastened at each overlap, whereby it presents a firm backing to receive the plaster. Furthermore, the illustrated form and correlation of the several elements provide a 20 very strong and light structure that may be quickly and cheaply produced from sheet metal.

Having thus described my invention, I claim as new, and desire to secure by Letters Patent:

A metallic partition, comprising spaced studding elements, each having oppositely projecting flanges along its vertical edges, channel plates at the top and bottom of the partition, the top plate presenting downwardly projecting flanges and the bot-

tom plate presenting upwardly projecting flanges, between which flanges the upper and lower ends of the studding elements are received, the studding elements being formed with vertical series of vertically ranging, elongated slots adjacent to the side flanges, the flanges of the channel plates having transverse holes adjacent to the upper and lower slots of the studding elements, ties securing the channel plates to the studding elements, said ties extending through the holes of the channel plates and the adjacent slots of the studding elements, stiffening members between adjacent studding elements, metallic lathing on the faces of the partition, ties securing the lathing to the studding elements, said ties passing through slots of the studding elements between the channel plates, and ties securing the lathing to the flanges of the channel plates, the lathing being in the vertical plane of the flanges of the channel plates and the latter having openings for receiving the last mentioned ties.

In testimony whereof I have signed my name to this specification in the presence of two subscribing witnesses.

CHARLES WILLIAM SANDERS.
